COLOR COMPARATOR

Clifford C. Hach and Max B. Kloster, Ames, Iowa, assignors to Hach Chemical Company, Ames, Iowa

Filed Feb. 28, 1972, Ser. No. 230,189

Term of patent 14 years

Int. Cl. D24—02

U.S. Cl. D32—2

FIG. 1 is a front perspective view of a color comparator showing our new design;

FIG. 2 is a front elevational view thereof;

FIG. 3 is a left side elevational view thereof;

FIG. 4 is a right side elevational view thereof;

FIG. 5 is a top plan view thereof;

FIG. 6 is a bottom plan view thereof; and

FIG. 7 is a rear elevational view thereof.

We claim:

The ornamental design for a color comparator, as shown.
